UNITED STATES PATENT OFFICE.

JEAN MARTIAL LOBIT, OF BROOKLYN, NEW YORK.

SLUG-TRIMMING KNIFE FOR LINE-CASTING MACHINES.

Application filed May 4, 1925. Serial No. 27,636.

This invention relates to knives which are used for trimming the side faces of type slugs after their delivery from the mold of type casting machines.

5 This knife is particularly designed for use with a mold which dresses the matrices along a line of feet so that any letters or other characters cast in a slug will define by their lower ends a single line even though 10 all of the letters are not of the same size.

My improvement has in view the production of a knife of the class described which will trim the slug to its proper body or depth depending upon the size of type desired and will gauge this depth from the 15 side of the slug that is at the feet of the type or caption base.

Other and incidental objects will be apparent hereinafter in the accompanying 20 specification and claims and shown in the drawings which, by way of illustration, show one and a preferred embodiment of the invention.

In the drawings:

25 Fig. 1 is a plan view of the knife supporting mechanism.

Fig. 2 is a rear elevation as mounted on the machine.

Fig. 3 is a cross-section on line 3—3 of 30 Fig. 2.

Fig. 4 is a view looking from the left of Fig. 2.

The fixed knife 1 is secured by means of a bracket 2 to a stationary frame portion 3 35 of the line casting machine. This knife cleans off the bottom side of the slug and is the gauge knife from which the depth of the slug is measured.

Four shafts 4 are provided for adjusting 40 the position of the movable knife 5. These shafts have sliding or finished portions of definite length which are fitted to slide in holes in the stationary frame. The ends of these shafts are of smaller diameter and form shoulders. Against the right hand shoulders, knife block 6 abuts, and against the left hand ones, adjusting block 7 abuts. These blocks are securely fastened to the 45 shafts by nuts 8.

50 Mounted on the adjustable block 7 is a bushing 9 having a threaded hole for receiving screw 10. At the right hand end of the screw is a cylindrical groove 11 formed by a head 12. Plate 13 is designed to engage the groove and is fastened to the sta-

tionary frame 3 by any suitable means, such as screws. This plate maintains screw 10 immovable in an axial direction and therefore causes blocks 6 and 7 to be moved whenever the shaft is turned by means of knob 60 14. The rotation of the screw serves to adjust the distance between knives 1 and 5, and the pitch of the screw bears a definite relation to this distance. The knob is divided into equidistantly spaced segments 65 defined by grooves 15 which are designated to indicate the depth of slug or point measurement of type. A latch 16 is provided to fit into the groove defining the setting of the movable knife, and lugs 17 on the knob are 70 for the purpose of aiding the operator to select the groove indicating the size of type more often used without the necessity of close observation. He need only turn the 75 knob until the finger which is against the desired lug contacts the protruding end of latch 16.

The distance between the two knives must exactly correspond with the position of the knob, and careful preliminary setting must 80 be made. This is done by providing slots in bracket 18 so that knife 5 can be adjusted for the size of slug indicated by the locked position of the knob. Screws 19 will keep the knife set in the position desired and a 85 plate 20 supported on screws 21 is an additional precaution to prevent lateral displacement during trimming operation. Lock-nuts 22 on the shanks of screws 21 constitute the means for receiving lateral pressure 90 from the knife and definitely securing the plate.

What I claim is:

1. In a line casting machine, the combination of a fixed knife for trimming a slug 95 along its caption base, a movable knife opposite thereto, a stationary frame, a movable frame for supporting said movable knife consisting of two blocks so disposed that one is supported on each side of said 100 stationary frame by shafts which are slidably mounted on said stationary frame, a threaded bushing in one of said blocks, and a screw passing therethrough for moving said movable frame in relation to said stationary 105 frame and fixed knife to vary the distance between the knives, said screw being axially fixed in relation to said fixed frame.

2. In a line casting machine, in combination with knives for trimming slugs of 110

variable depths measured from their caption base, a fixed knife for trimming the faces of slugs along their caption bases, a stationary support for said fixed knife, a 5 knife for trimming the other side of said slugs, a movable block for supporting said last named knife, a plurality of shafts for supporting said block, another block secured to said shafts, a nut in said last named block, 10 and a screw engaging said nut and axially held in said support, the rotation of said screw serving the purpose of varying the distances between said knives.

3. In a line casting machine, in combination with knives for trimming slugs of 15 variable depths measured from their caption base, a fixed knife for trimming the faces of slugs along their caption bases, a stationary support for said knife, a knife 20 for trimming the other side of said slugs, a movable block for supporting said last named knife, a plurality of shafts slidably mounted in said stationary support for supporting said movable block, another block 25 fastened to said shafts and disposed on the opposite side of said stationary support from said movable block, a screw having one end rotatively mounted in said stationary support and having threaded relation with said 30 movable block, and a knob on said screw for rotating the same to displace the blocks

and shafts so as to vary the distance between knife edges.

4. In a line casting machine, the combination of a fixed knife for trimming a slug along its caption base, a support for said knife, a plurality of rods slidably mounted in said support, blocks fastened to said shafts one on each side of said support and in definite spaced relation, a knife adjustably mounted on one of said blocks, a threaded bushing on the other of said blocks, a screw for engaging said threaded bushing, means to hold said screw from axial displacement, said means being fixed relative to said support, and a graduated knob for rotating said screw to slide said blocks and vary the distance between said knife blades.

5. In a line casting machine, the combination of knives for trimming slugs of 50 variable depths measured from their caption bases, comprising a fixed knife for trimming the faces of slugs along their caption bases, a movable knife for trimming the other side of the slugs, support means for said knives, 55 and means extending from and coacting with said support means for enabling adjustment of the distance between said knives by movement of the movable knife.

In testimony whereof I hereto affix my 60 signature.

JEAN MARTIAL LOBIT.
